UNITED STATES PATENT OFFICE.

WILLIAM EMSLEY MORSE, OF RAPID CITY, SOUTH DAKOTA.

AUTOMATIC HUMIDIFIER.

Application filed August 26, 1924. Serial No. 734,343.

The present invention relates to new and useful improvements in appliances for the fuel system of internal combustion motors, and it pertains more particularly to a device 5 for humidifying air introduced into the carburetor or charge-forming device of the fuel system.

It is one of the primary objects of the invention to provide means for causing the 10 air introduced into a carburetor or similar charge-forming device of an internal combustion motor to pass in the presence of water, in order to cause the air to take up moisture before entering the charge-forming 15 device.

It is a further object of the invention to construct a device of this character in such a manner that the water is maintained at a predetermined level.

20 It is a further object of the invention to provide a means in which the air will be caused to pass at all times in the presence of the water before entering the charge-forming device.

25 It is a still further object of the invention to provide a mixing means which will cause a thorough mixing of the air and water.

30 With the above and other objects in view, reference is had to the accompanying drawings, in which—

Figure 1 is a vertical sectional view of a device constructed in accordance with the present invention and shown attached to a carburetor or other charge-forming device, the carburetor being shown in dotted lines;

Figure 2 is a top plan view of a device removed from the carburetor.

Referring more particularly to the drawings, the carburetor is designated by the reference character A, and the humidifying device forming the subject matter of the present invention is designated by the reference character B. The humidifying device 40 comprises a container 5 having a tapered lower section 6 terminating in a tubular end or extremity 7. Leading from the body portion 5 there is an arm 8, which is adapted for engagement with the intake of the charge-forming device A. The body portion 5 of the container is partially closed by means of a cap 9 secured by means of screws or the like, 10, and such cap 9 has a centrally disposed air opening or intake 11 therein. Depending from the cap 9 there is a flange 12, and depending from said flange and carried

thereby there is a cylindrical air-directing shell 13 which is circular in form and arranged substantially concentric with the body 5.

Depending from the lower end of this shell 13, there is a conical-shaped member 14 of suitable wire mesh, and this projects to a point approximately half way between the ends of the tapered portion 6. The reference numeral 15 designates a water inlet which is connected by means of a coupling 16 to the cap 9 heretofore mentioned, and said coupling is provided with a valve seat 17 with which a valve 18 is adapted to engage to shut off the supply of water through the pipe 15. This valve 18 is controlled by means of a float 19, which float is maintained upon a rod or the like, 20, the lower end of which has sliding engagement in a bearing 21 carried by a partition 22. Mounted adjacent this partition 22, there is a suitable drain cock 23.

The reference numeral 24 designates a universal coupling carried by the upper end of the rod and pivotally connected to this universal coupling there is a lever 25, which lever 25 is pivotally mounted in an arm or bracket 26. The pivotal point of this lever 25 is intermediate of its ends and the valve 18 is connected to that end of the lever 25 not connected to the universal coupling 24. Carried by the rod 20, there is a fan wheel 27 adapted for rotation within the cylindrical air-directing shell 13 for a purpose to be hereinafter described.

Secured to the inner face of the conical portion 6 of the body there is a downwardly directed flange 28, and such flange serves as a splash guard to prevent the fluid contained in the lower conical portion from splashing upwardly around the cylindrical sheet metal member 13. The reference numeral 29 designates an overflow tube, and such overflow tube projects through the conical portion 6 of the body and has an extension 30 by means of which excess fluid may be discharged from the conical portion 6 of the body should it accumulate therein.

The device operates in the following manner:

Upon a vacuum or partial vacuum being created in the charge-forming device A by the operation of the motor (not shown) air is drawn in through an intake opening 11 and causes a revolving of the fan blade 27. The air then passes downwardly

through the cylindrical air-directing shell 13 and upwardly through the arm 8 to the charge-forming device, the air having passed in the presence of the water contained in the bottom of the tapered portion 6.

As the water is introduced into the device it passes in the presence of the screen 14 and a certain portion of such water is retained upon the screen so that the air 10 passing inwardly of the device passes in the presence of this water also. The valve 18 controlling the supply of water is operated by the float 19 and the float maintains the valve in closed position so long 15 as the proper volume of water is present in the tapered portion 6. However, upon the falling of the level of water in the tapered portion 6, the valve 18 is opened to permit the introduction of a fresh supply.

20 The operation just described is true when the device is in advance of a charge-forming device and connected to the air intake thereof. The device has other uses, however, such, for example, as interposition between 25 the charge-forming device and the internal combustion motor, in which case the discharge or outlet of the charge-forming device would be connected with the intake 11 of the device and the arm 8 of the device 30 would be connected with the manifold or intake ports of an internal combustion motor. When used in the last-mentioned connection, the charge formed by the charge-forming device is passed through the device 35 and the rotating blade 27 causes a thorough mixing and commingling of the elements thereof.

It is obvious that the supply opening 11 may be provided with a suitable cock in 40 order that the supply of air may be permanently shut off, and this pipe may also be provided with a suitable heater for use in low temperatures, if desired.

From the foregoing it is apparent that 45 all of the objects of the present invention have been accomplished, and, further, it should be understood that numerous modifications of structure might readily be resorted to without in the least departing 50 from the scope of the claims.

What is claimed is:

1. A humidifying device, for moistening air passing to an internal combustion engine, comprising a housing having a water

inlet and an air inlet, a valve for controlling 55 the water inlet; a float carrying shaft suspended in the housing, means for operating the valve from said shaft, an air-directing shell in the housing, a wire mesh member secured to the lower end of the shell, and 60 a fan on the shaft in the shell.

2. A device of the character described comprising a housing, a shell mounted within 65 the housing and spaced from the side walls thereof, a conical fabric member projecting from the lower end of said shell, a water inlet for the housing, an air inlet for the housing, and an agitator mounted within 70 said shell and within the path of the incoming air and water whereby a mixing 75 of air and water is had within the housing.

3. A device of the character described comprising a housing, an air inlet therefor, a water inlet therefor, a valve for controlling the water inlet, and means for controlling the valve, said means comprising a vertically disposed rod, a fan carried thereby, a float carried by the lower end of said rod, and a lever connecting the rod and valve whereby upon movement of the float 80 the rod will be moved to open or close the valve through the medium of said lever.

4. In an air moistener, a substantially cylindrical body member having a tapered lower portion, a cylindrical shell mounted 85 within said cylindrical body portion, a conical gauze member carried by said shell and projecting into the tapered portion of the body member, means for introducing water to said gauze member, means for introducing air to said gauze member, and means 90 for mixing said water and air, said means being mounted within the cylindrical shell and comprising a vertically disposed rod and an agitator mounted thereon for operation 95 of the incoming air and water.

5. A device of the character described comprising a body portion, an air-directing shell mounted within the body portion and conforming in shape thereto, said shell being spaced from the walls of the body portion, a gauze member of conical form projecting from the lower end of said shell, and a splash plate carried by the walls of 100 the body portion and projecting to a point 105 adjacent said conical gauze member.

WILLIAM EMSLEY MORSE.
